UNITED STATES PATENT OFFICE.

JOHN L. WHEELER, OF ST. LOUIS, MISSOURI.

THREAD-CONTROLLING MECHANISM FOR LEATHER-SEWING MACHINES.

1,182,948.

Specification of Letters Patent.

Patented May 16, 1916.

Application filed November 17, 1913. Serial No. 801,376.

To all whom it may concern:

Be it known that I, JOHN L. WHEELER, a citizen of the United States, and resident of St. Louis, Missouri, have invented certain new and useful Improvements in Thread-Controlling Mechanism for Leather-Sewing Machines, of which the following is a specification.

This invention relates to improvements in an attachment for leather sewing machines, and has for its object a mechanism for drawing the thread providing a sufficient slack to be passed around the shuttle, a means for clamping the thread while the slack is being formed, a means for puncturing the leather and feeding the same sidewise, bringing the perforation in proper alinement with the needle; and a means for adjusting the amount of slack.

A further object of my invention is to construct a device to be used in connection with a sewing machine on which leather is sewed, the said device being operated by cams for clamping the thread when a portion of the device is forming a slack in the thread to be passed around the shuttle, a means for adjusting the length of the slack and a means for setting the stitch.

Figure 1, is a side elevation of my invention with parts in section showing the general arrangement and construction. Fig. 2, is a front view of the same. Fig. 3, is a detail side elevation of the combination auxiliary take-up slack forming, and thread measuring lever with a portion thereof in section. Fig. 4, is a detail cross-sectional view of the eccentric for regulating the throw of the stitch set lever. Fig. 5, is a side elevation of the cam made use of for operating the needle. Fig. 6, is a side elevation of the cam used for operating the combination auxiliary take-up, slack forming and thread measuring lever. Fig. 7, is a side elevation of the cam made use of for operating the puncturing lever. Fig. 8, is a side elevation of the cam made use of for operating the stitch set lever after the thread has been passed around the shuttle through the material by the combination auxiliary take-up slack forming and thread measuring lever. Fig. 9, is a detail sectional view of the tension mechanism by which the

thread is controlled in being unwound from the spool. Fig. 10, is a detail sectional view of the material sewed showing the formation of the stitch made by the machine.

Referring to the drawings in detail 11 indicates the bed-plate of a sewing machine, such as is used for sewing shoes, harness, or other leather.

12 indicates the shuttle casing, 13 the shuttle, and 14 a presser foot under which the material is fed and by which said material is held in position during the puncturing and sewing of the same.

15 indicates a shaft on which is mounted a fly wheel 16, and to which is attached a handle 17, when the device is to be rotated and operated by hand. But on said shaft 15 may also be located a pulley so that the 70 device can be operated by power. The shaft 15 is supported in bearings 18 and on said shaft are mounted disks 19 and 20. Both surfaces of each disk are provided with cam grooves in which rollers attached to certain levers operate. The function of these levers will be hereinafter described.

On the machine is located a rigid supporting frame 21 on which is mounted a wax-pot 22 provided with grooved thread 80 guide rollers 23, and a submerged roller 24 under which the thread is guided through the wax. On one of the arms of the supporting frame is rigidly attached a segment frame 25 which is provided with an adjustable bracket 26. On this bracket is mounted a guide wheel 27 over which the thread operates. At one end of the segment is located a similar wheel 28 over which the thread leading from the spool is passed; this spool 90 is preferably located beneath the bed-plate or table of the machine.

On the opposite end of the segment 25 is pivotally mounted a lever 29, and on the pivot 30 supporting the same is mounted a cam disk 31, the same being so situated that its lower periphery is brought in contact with the thread firmly clamping the thread between the disk and a table 32 formed on the arm of the support 21, when 100 the lever 29 is raised upwardly by a roller 33 located on its free end coming in contact with a projection 34 formed on the periphery of the cam disk 20.

On the bottom of the bed-plate is formed an ear 35 to which is pivoted a combination auxiliary take-up, slack forming and thread measuring lever 36, this lever is provided with a roller 37, shown by dotted lines in Fig. 1, and this roller extends into the cam groove 38 formed on the outer surface 39 of the cam disk 19. This said lever projects upwardly and under the upper end of the same an arm 40 is pivotally mounted, the upper end of this arm is provided with a groove guide wheel 41 under which the thread passes before passing over the table 32. The arm 40 is provided with a piston 42 operating in a piston chamber 43 located on the upper end of the lever 36. In this chamber is located a spring 44 which regulates the pressure on the thread when the combination auxiliary take up and thread measuring device is measuring off a proper amount of thread for the various thicknesses of material. On the lever 36 are also located pins 45 and 46 which are so positioned as to limit the movement of the arm 40, the general construction and arrangement of these parts are fully shown in Fig. 3.

On the supporting bracket 21 is pivotally located a lever 47, its free end provided with a roller 48 which projects into the cam groove 49 formed on the outer surface 50 of the cam disk 20, and by the rotation of this cam disk the lever 47 is operated bringing the eccentric 51 in contact with the surface 52 of the stitch setting lever 53 which is located on the pivot 54 which pivot also supports the lever 47. The downward movement of the stitch setting lever 53 is limited by the pin 55 located on the bracket 21 and the upward movement of the stitch setting lever 53 is governed by the adjustment of the eccentric 51.

In the frame or bracket is located a shaft 56 which is slidably and rotatably mounted and on this shaft is rigidly attached a lever 57, its one end being provided with a roller 58 shown by dotted lines in Fig. 1, which projects into a cam groove 59 located on the inner surface 60 of the cam disk 20. The opposite end of the lever is provided with an awl or perforating pin 61 which passes through the opening 62 formed on the presser foot 14 and punctures the material which lies between the presser foot and the surface 63 of the shuttle casing. The lateral movement is imparted to the shaft 56 and lever 57 by means of the pivoted arm 64 which is operated when the projection 65 formed on the cam disk 20 contacts with the end 66 of the arm 64, pressing it outwardly and bringing the end 67 of the arm against the shaft 56 on which the lever 57 is mounted, pressing the same toward the left, an amount equal to the stitch and in lines with the needle 68 located in lever 69. After the awl or perforating pin has perforated and fed

the material, the spring 69^a located between the lever 57 and the lever 69 shifts the awl back to the right, for the next stitch.

The lever 69 to which the needle 68 is attached is operated at a proper period by means of the cam groove 70, formed on the inner face 71 of the cam disk 19 into which a roller 72 carried by the opposite end of the lever 69 projects.

All of the cams are so positioned as to operate each one of the several levers at the proper time so that the material is punctured and fed in alinement with the needle, the thread properly adjusted forming sufficient slack to be passed around the shuttle and by the operation and arrangement of the levers a lock stitch is formed as that illustrated in Fig. 10. The specific feature is to pull the loop 73 into the material as shown, and this forming and pulling in of the loop is accomplished by the stitch setting lever 53 operated in connection with the movement of the lever 47. By my arrangement of the thread which has been properly waxed and passed through the material and the other thread passing through the loop formed, is drawn up into the material at a distance governed by the adjustment of the cam 51 regulating the throw or upward movement of the stitch setting lever 53, and whether the horizontal portion 74 of the thread is worn out or not the loop inside of the material acts as a lock and holds the stitch, preventing the same from withdrawing from the material.

The adjustment of the thread to be provided for the greatest thickness of material to be sewed is accomplished by sliding the block 26 forwardly or rearwardly on the segment 25, thereby allowing the wheel 41 on the lever 40 to come in contact with the thread at a certain predetermined position, and in conjunction with the spring 44 and pin 42, regulates the amount of thread pulled from the spool. This drawing in of the thread or stitch takes place when the thread is locked on the table 32 by the cam 31. The sliding block 26 is held on the segment 25 by the clamping screw 75 and the thread wheel 27 is attached to the arm 76 which is formed integral with the sliding block 26. See Fig. 2.

On the base or table of the machine is located a tension device 77 through which the thread from the spool is passed. This tension device consists of a disk 78 which is loosely mounted on a stud 79. Said stud is screw-threaded on one end and on the threaded portion is located a tension regulating wheel 80. Between the tension regulating wheel 80 and the disk 78 is located a spring 81. This tension device is used to regulate the supply so that by movement of the lever 36 the thread will not form a greater loop than is determined by the ad-

justment of the block 26, and also to prevent the thread from unwinding rapidly from the spool and becoming tangled.

The operation of my invention is as follows: The thread after having been placed in position as illustrated in Fig. 1, the material to be sewed is passed between the presser foot and the surface 63, then the lever 57 is operated bringing the awl 61 down through the material, when in such position the projection 65 on the face of the cam disk 20 contacts with the pivot arm 64 pressing the shaft 56 to one side thereby shifting the lever 57 and awl 61 to the left; the awl still being through the material this movement feeds the material so that the perforation is in direct alinement with the needle 68. When in this position the projection 65 having performed its function, the lever 57 raises to its normal position and at the same time is shifted back to its normal position by the coil spring 69a. At this junction the lever 69 is operated elevating the needle 68, catching the thread which passes over the thread-guide 82, and presser foot 14. The lever 69 then draws the needle downwardly as the lever 36 moves forward to allow the proper amount of thread to go around the shuttle allowing the shuttle to catch the thread and drawing it around, this shuttle is of the ordinary rotary construction. The lever 36 then starts back to the rear drawing the loose thread from around the shuttle up to the under surface of the material being sewed. When this is accomplished the thread is locked between the cam 31 and the table 32, the lever 36 continues its rearward movement and draws sufficient thread from the spool to form the next stitch, the lever 47 now commences to operate and draws the lever 53 upwardly pulling the thread into the material sewed, the thread being clamped between the eccentric and table is held tightly so that the thread from the shuttle is drawn into the material. When this thread is drawn into the material the thread

is released from its locked position between the eccentric and the table and the operation repeated.

50

Having fully described my invention what I claim is:

1. Thread controlling mechanism for leather sewing machines comprising in combination, a main frame, a stitch setting lever mounted thereon, a combined take up and thread measuring device including a lever pivoted on said main frame, a thread lock adapted to lock the thread between said stitch setting lever and said take-up and thread measuring device, a segment frame concentric with the pivot of said pivoted lever, and having an adjustable thread guide thereon, said take up and thread measuring device being adapted to act on the thread between said thread lock and said adjustable thread guide, whereby the action of said device on the thread may be varied by the adjustment of said thread guide.

2. Thread controlling mechanism for leather sewing machines, comprising in combination a base plate, a main frame mounted thereon, a plurality of cams axially mounted in the main frame, a combined take-up and thread measuring device including a lever pivoted on said main frame and operated by said cams, a segment frame concentric with the pivot of said pivoted lever, an adjustable thread guide located on the segment frame by which the slack of the thread is regulated, a binding lever located at one end of the segment frame by which the thread is gripped during the thread measuring operation, all of said levers being operated at proper intervals by the movement of said cams, substantially as specified.

In testimony whereof, I have signed my name to this specification, in presence of two subscribing witnesses.

JOHN L. WHEELER.
